MEMORY MATRIX FRAMES

Frank Joseph Wood, Chandlers Ford, England, assignor to The Plessey Company Limited, Ilford, England, a British company

Original application Feb. 20, 1958, Ser. No. 716,496, now Patent No. 3,126,526, dated Mar. 24, 1964. Divided and this application Nov. 6, 1963, Ser. No. 321,740

2 Claims. (Cl. 29—155.5)

This application is a division of U.S. application Serial No. 716,496 filed February 20, 1958, now U.S. Patent No. 3,126,526 granted March 24, 1964.

This invention relates to memory matrix frames of the type in which a number of individual magnetisable annular cores are threaded on the wires of a network or mat of wires extending in different directions in such manner that while each wire of each of a number of sets having different directions passes through a number of individual cores, only one core is passed through by both of two wires each belonging to a different set. It is common practice to mount the mats formed of two, or in some cases more, sets of wires associated with and passing through a series of cores, in a frame, in which the wires are secured in a taut position. This has hitherto been effected by securing in or on the frame, along the sides thereof, an appropriate number of terminal tags, posts, or the like, to which the ends of the individual wires were respectively secured by soldering or the like, and which served as terminals for the external connections to the matrix wires, these external connections being again normally effected by soldering. The present invention has for an object to provide an improved arrangement capable of simple manufacture and permitting close spacing of terminations.

According to the invention the matrix frame is built up of two frame laminae secured to each other face to face, with the matrix wires extending through the joint between the two laminae so as to be secured to the frame by the cement or the like joining the two laminae. Each frame lamina may further be composed of one, two or four component parts such as limbs or half-frames as convenient. Preferably the mat is built up on one of the frame laminae in a jig including means for keeping the frame wires taut across the said frame laminae and in contact with the latter, and the second frame lamina is then placed on top of the first frame lamina and the wires extending across the latter, after the application of a cement or other binding means, whereafter the two frame elements are pressed against each other, heat being applied at the same time where necessary or desirable according to the kind of cement or the like employed, and after the cement or other binding means has set or hardened to the desired extent, the frame with the mat is removed from the jig after the wires have been cut or detached from the jig. The cutting is effected in such manner that wire ends suitable to form connector terminals project from the outer side of the frame. These projecting wire ends are preferably tinned by conventional methods to facilitate soldering other wires, for example of other matrices.

The invention will now be described in more detail by way of example with reference to the accompanying drawing.

FIG. 1 is a schematic perspective view of a mat of memory cores with two sets of wires extending at right angles to each other, part of the upper lamina being broken away for greater clearance.

FIG. 2 similarly illustrates a simple form of jig suitable for carrying out the invention, and

FIG. 3 is a sectional elevation of the jig in use.

Referring now to the drawings, the annular cores, which may consist of so-called square-loop ferrites, are referred to by reference numeral 1, and the two sets of wires by 2 and 3 respectively, while the matrix frame consists of two laminae 7 and 9, preferably made from fabric-based or paper-based or fibre-glass based plastic sheet. The wires 2 and 3 are secured in a taut condition in a jig comprising a plywood frame 4 having a central aperture 5 corresponding to the size of a matrix proper, this aperture being surrounded by a recessed shoulder 6 adapted to accommodate one lamina 7 of the matrix frame according to the invention in such manner as to be flush with the surface of the plywood frame 4. Pins 8 extend along the other sides of the jig 4 for securing the wires 2 and 3 after the same have been duly tightened. After or before the wires have been tightened and secured as described, a strong cement, for example, the cement known under the registered trademark Araldite, which is of the thermosetting kind, is applied and the second lamina 9 is placed on top of the lamina 7, with the wires interposed between the two frame laminae 7 and 9. These laminae are then bonded together by curing under pressure at the requisite temperature, whereafter the bonded plastic frame with the wire mat can be removed from the jig, for example by cutting the wires just above the pins 8. This leaves straight connector ends 10 of each wire projecting outwardly from the outer edge of the frame. These projecting ends may, if required, be tinned adjacent their outer ends by a rapid-dip soldering technique.

It will be readily appreciated that the invention is not limited to all the details of the example described. Thus it is not necessary for each frame lamina 7 and 9 to be one integral piece, but one or each may be built up of a number, preferably 2 or 4, of abutting pieces provided that the butt joints of the two laminae are offset relative to each other. Furthermore the jig may be varied in a number of ways which will be obvious to those skilled in the art, for example by providing individual tightening means for each wire, or in some cases by providing spring tensioning devices or clamping plates. The tightening means may, if desired, be of the kind commonly used for the strings of musical instruments such for example as pianos or violins.

I claim:

45. 1. A method of constructing a magnetic memory matrix, having a wire mat and magnetic cores threaded on the wires thereof, comprising providing a construction jig having means for supporting and locating a frame lamina with one of its main surfaces exposed and means for locating the wires of a mat thereon and for attaching the ends of the wires thereto with intermediate portions of each wire in contact with such lamina, placing and locating a frame lamina on said jig, building up the wire mat by threading each wire through the appropriate cores, locating and tightening such individual wires on the jig while attaching the ends of each wire to the jig, placing a second frame lamina over the first-mentioned lamina and said wires with the interposition of a layer of adhesive material between said laminae, applying pressure to press said laminae together, while causing the adhesive to set, severing the network wires at points spaced outwardly from the frame lamina, and removing the complete matrix from the jig.
50. 2. A method of constructing a magnetic memory matrix of the type comprising a quadrilateral frame with at least two sets of substantially parallel, flexible, electric conductor wires extending in substantially different directions between each set extending between two sides of said quadrilateral frame and a plurality of individual toroidal cores of magnetizable material held by said sets
- 55.

- 65.
- 70.

of wires, one core at each of the intersections of the wires of said sets, the steps comprising,
 providing two quadrilateral frame laminae,
 providing a jig with a quadrilateral opening and a recess
 surrounding said opening adapted to receive one of 5
 said quadrilateral laminae,
 fitting a first of said quadrilateral laminae in said
 recess,
 stringing wires of said sets across said opening in said
 jig while inserting the cores thereon, 10
 tightly fastening the two ends of each of said wires
 of the sets to the jig in region outside of said recess,
 applying a layer of cement to the surfaces of said recess
 crossed by said wires,

affixing a second of said laminae to the first by means
 of said cement with the wires crossing the laminae
 embedded therebetween, and
 releasing said wire ends from said jig and removing
 the wired frame therefrom.
